(57) **CLAIM**

The ornamental design for hinge, as shown and described.

DESCRIPTION

FIG. 1 is a top front perspective view of a hinge incorporating our new design;

FIG. 2 is a top rear perspective view thereof;

FIG. 3 is a top view thereof;

FIG. 4 is a left side view thereof;

FIG. 5 is a bottom view thereof;

FIG. 6 is a rear view thereof;

FIG. 7 is a front view thereof;

FIG. 8 is a front bottom perspective view thereof, showing the hinge in a closed position; and,

FIG. 9 is a front bottom perspective view thereof, showing the hinge in a partially opened position.

The right side view of the hinge of FIG. 1 corresponds to the left side view of FIG. 4.
